Primary Examiner — Cynthia Ramirez(74) *Attorney, Agent, or Firm* — Calfee, Halter & Griswold LLP(57) **CLAIM**

The ornamental design for a faucet cartridge, as shown and described.

DESCRIPTION

FIG. 1 is a perspective view of a faucet cartridge of the design; FIG. 2 is a front elevational view, the rear being a mirror image thereof;

FIG. 3 is a left side elevational view, the right side being a mirror image thereof; and,

FIG. 4 is a top plan view thereof.

The portions of the Figures shown in broken lines are not part of the claimed design and are for illustration only.

1 Claim, 3 Drawing Sheets(56)
